CLAIM

The ornamental design for over door organizer, substantially as shown and described.

DESCRIPTION

FIG. 1 is a front perspective view of over door organizer, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict stitching, and form part of the claimed design.

The cross-hatch shading shown in the drawings illustrates texture, and while shown intermittently, is understood to extend uniformly across the entire surface of the design upon which it is applied.
